J. F. CALLAHAN
HÆMOSTATIC FORCEPS

Filed Sept. 28, 1922

UNITED STATES PATENT OFFICE.

JOHN F. CALLAHAN, OF BROCKTON, MASSACHUSETTS, ASSIGNOR TO ISABEL G. CALLAHAN, OF BROCKTON, MASSACHUSETTS.

HÄMOSTATIC FORCEPS.

Application filed September 23, 1922. Serial No. 591,127.

To all whom it may concern:

Be it known that I, JOHN F. CALLAHAN, a citizen of the United States residing at Brockton, in the county of Plymouth and 5 State of Massachusetts, have invented new and useful Improvements in Hämostatic Forceps, of which the following is a specification.

The present invention relates to forceps 10 adapted to clamp a bleeding point and to guide to the point thus clamped a thread or cord which is adapted to be tied around the point. Fundamentally the present invention is of the same nature as that disclosed 15 in my prior Patent No. 1,460,531, granted July 3, 1923, in that it relates to an instrument combining a pair of clamping jaws with holding and guiding means for the ligature cord. As compared with the prior 20 invention, my present object is to enable the ligature to be tied about the tissue outside of the bite of the forceps jaws; in other words, to make possible the ligating of a bleeding point in certain circumstances where it is 25 not possible to take so deep a bite of the tissue by the jaws as is required in the case of my former invention. This object is accomplished by the provision in the forceps of means for holding a loop of thread close 30 to the gripping ends of the forceps jaws, and in other characteristics of relative location and shape of said jaws and of the thread holding means, by which it is possible 35 over the ends of the jaws and to draw it tight about the included tissue where it is wholly clear of the jaws.

In further explanation of the principles and characteristics of the present invention, 40 attention is directed to the following description in detail of the preferred embodiment of the invention, and to the drawings referred to in said description.

In the drawings:—

45 Figure 1 is a fragmentary side view of a hämostatic forceps embodying the invention, one of the gripping jaws being represented as broken away so as to show the gripping face of the other jaw.

50 Figure 2 is a plan view of one side of the complete forceps.

Figure 3 is a plan view of the opposite side of the forceps.

55 Figures 4 and 5 are plan views showing the use and operation of the forceps for

grasping a bleeding point, and the operation of ligating the point so grasped.

Figures 6, 7 and 8 are side views of the forceps showing the same use and operation.

Figure 9 is a fragmentary view showing 60 the completed ligature.

The forceps consist of two long and springy arms *a* and *b* pivoted together at *c* and having finger loops *a'* and *b'*. These arms are extended beyond the pivot to form 65 jaws *a*² and *b*². A spring clip *d* is mounted on one of the arms to hold the ends of a cord for making a ligature and complementary teeth *e* and *f* are formed on the arms to interlock and hold the forceps in 70 closed position.

The parts of the forceps thus far described comprise only matters of common practice. The new step in the invention concerns the formation of the extremities of the 75 gripping jaws, and the association therewith of holding fingers for a loop of the ligature cord. Such formation and arrangement obtain valuable new results, and are important. First as to the means for 80 holding the loop of the cord. This means comprises two fingers or prongs *g* and *h*, of which one is formed on the under side of the jaw *a*², and the other on a corresponding part of the jaw *b*², close to the ends of 85 the jaws. The notch or opening *i* between the fingers and the adjacent jaws provides a space in which the loop or bight of a cord *j* may be placed, the ends of the cord being brought around the outer sides of the 90 jaws and carried up to and passed under the spring clip *d*. A single knot may be formed in the cord before the ends of the latter are brought under the clip as shown in Figures 2 and 4, but whether or not this 95 is done is a matter for the judgment of the surgeon, as the first knot can be tied after the forceps have been clamped on the bleeding point and the cord disengaged from the clip.

100 A feature of formation of the jaws is that they are recessed in their sides next to one another as to substantially their whole length except for a short and narrow gripping face *h* at the extremity. This gripping face is so short that its inner termination comes outside of the bottom of the notch *i*, or at least, does not extend any further than such bottom from the extremity of the jaws. 105 In addition the outer faces *a*³ and *b*³ of the 110

jaws near their extremities are steeply inclined to one another and each of such faces is also steeply inclined to the plane of the adjacent gripping face, as is shown in the 5 plan views, and the upper and under faces are inclined at a relatively large angle to one another, at the extremities, as shown in Fig. 1 with respect to the jaw b^2 , such faces being identified at b^4 and b^5 . In particular 10 it is to be noted that the under side b^4 of the jaw, which forms the upper boundary of the notch i , is inclined at a substantially large angle to the longitudinal dimension of the jaw. The steep inclination of said outer 15 or exterior faces a^3 , b^3 , b^4 and b^5 begins at that part of the jaws where the fingers join them; or in other words, the outer faces of each jaw are steeply inclined convergently from the plane, transverse to the longitudinal 20 dimension of the jaw, lying about at the bottom of the notch i . The approximate location of the plane referred to is indicated by the broken line $x-x$ of Figure 1. These characteristics of the jaws tend to cause the 25 loop of thread, when a knot is tied in it, as shown in Figure 2, and is drawn tight, to slip over and from the ends of the jaws without any other agency than the force applied in drawing the knot tight.

30 When the forceps are threaded, that part of the thread which passes between the holding fingers of the two jaws, although close to the gripping surfaces of the jaws, cannot be caught or fouled by these surfaces 35 where they grip the bleeding point, because this stretch of cord is simply pushed back by the tissue into the recessed open space between the jaws when the jaws are forced into the tissue to bite the bleeding point.

40 This condition is illustrated in Figure 4, where l represents a mass of live tissue and m the end of a severed artery which it is the surgeon's purpose to ligate. It is to be assumed that the orifice of the artery is at 45 the surface of the tissue. In order to grip the artery and check the flow of blood, the open jaws have to be pressed into the tissue on each side of the artery, but when this is done the part j^2 of the cord which runs across from one jaw to the other is pushed back out of the way by the included tissue. Even though in being thus pushed back, and at the same time slackened with the 50 approach of the jaws to one another, it is also brought between them, it is not gripped because the recessed formation of the jaws on their inner faces, and the fact that the holding notches extend at least as far back as the terminations of the gripping faces k ,

55 and preferably beyond them, insure that the interposed cord will not be gripped and held fast. When the jaws are closed, they are held so by the teeth e and f , leaving the surgeon free to use both his hands, if need 60 be, in tying the cord.

The fingers g , h , terminate slightly outside of the planes of gripping faces k , and this fact, together with the relation of the notches to the inner termination of these faces, brings the result that, when the forceps are closed, the tissue is not gripped by the fingers, but is forced into the space between the fingers by the pressure of the gripping faces upon the excess tissue in the bite of the jaws. This tissue, being forced 70 between the fingers and held in front of them by the gripping faces, holds the ligature cord in the bottoms of the notches, thus preventing the cord from slipping out of position; but when force is afterwards applied in tightening the knot the loop of the cord easily slips over and around the tissue between the fingers.

The action of pulling up on the ends of the cord to tighten the knot makes the loop 80 progressively smaller until it is only just large enough to surround the extremities of the jaws. When it has been brought to these small dimensions the parts of the jaws which it surrounds are those parts having steeply 85 inclined surfaces, wherefore the further continued drawing up of the knot simply crowds it off from the forceps and around the gripping point. Then the knotted loop is confined in a space where tightening of 90 the knot can have no other effect than to draw the loop closely around the tissue and clear of the forceps jaws. The fact that the notch i extends back of or as far back as the gripping faces k leaves that part of the cord 95 which is contained in the notches free to run through them, and enables the loop to be drawn up and tied tightly around the gripped tissue.

Figure 4 shows the situation when the 105 jaws have been pressed into the tissue and just before they have been closed on the bleeding point. In Figure 6 the jaws have been closed, but the knot has not been drawn tight. Figures 5 and 7 show the knot after 110 it has slipped clear of the forceps, and Figures 8 and 9 show it after it has been drawn tight about the bleeding point.

Stating the characteristics of the jaws and cord holding prongs in a general way, 115 it may be said that such prongs are in parallel with the gripping jaws, meaning by this expression to point to the fact that the prongs are at nearly the same distance from a plane intermediate the jaws as the inner 120 or gripping faces of the jaws themselves. In other words, although the prongs are slightly outside of the planes of the gripping faces, as previously stated, yet they are intermediate these planes and the outer sides 125 or faces of the jaws. The prongs lie in planes which extend longitudinally of the respective jaws and parallel to said gripping faces, which planes are also located intermediate the inner and outer sides of the 130

jaws. This relation is the same as that previously indicated in the statement that the prongs are on the under sides of the jaws, but is not subject to qualification by the position in which the forceps are held. Owing to this arrangement the cord is securely held so that it cannot accidentally slip over the ends of the jaws or back from the position where it should be, but at the same time is able to be slipped readily from the jaws when necessary.

What I claim and desire to secure by Letters Patent is:

1. Hæmostatic forceps having jaws formed with gripping faces at their extremities only and being recessed away from one another back from said extremities, each jaw having an external thread-holding finger adjacent to its said extremity, both fingers being at the same side of the forceps.

2. Hæmostatic forceps having jaws formed with gripping faces at their extremities and recessed away from one another back from said extremities, said jaws both having thread-holding fingers adjacent to said extremities, the outer faces of the jaws being steeply inclined convergently toward their extremities from a transverse plane at the bottom of the notches between the fingers and the jaws.

3. Hæmostatic forceps having jaws formed with gripping faces at their extremities and recessed away from one another back from said extremities, said jaws having thread-holding fingers adjacent to said extremities, the outer faces of the jaws adjacent to their extremities being steeply inclined convergently toward said extremities from a transverse plane located approximately at the bottoms of the after mentioned notches, there being between each jaw and its associated finger a cord-receiving notch extending inward from the jaw extremity as far as the inner limit of said gripping face.

4. Hæmostatic forceps having jaws formed with gripping faces at their extremities and recessed away from one another back from but close to said extremities, said jaws having thread-holding fingers adjacent to said extremities, said fingers being arranged in planes parallel to said gripping faces and located intermediate the inner and outer sides of the jaws.

5. Hæmostatic forceps having jaws formed with gripping faces at their extremities and recessed away from one another back from said extremities, said jaws having thread-holding fingers adjacent to said extremities, said fingers being located at the under sides of the jaws and at approxi-

mately the same distance from one another as the recessed inner faces of the jaws.

6. Hæmostatic forceps having jaws constructed to grip at their extremities, but being recessed back from said extremities so as to limit the gripping area, and the jaws being formed with open notches to receive the loop of a cord, and said notches being both at the same side of the forceps and extending back as far as the rear limit of the gripping area.

7. Hæmostatic forceps having jaws constructed to grip at their extremities, but being recessed back from said extremities so as to limit the gripping area, and the jaws being formed with open notches to receive the loop of a cord, and said notches being both at one side of the gripping part and extending back as far as the rear limit of the gripping area, the surfaces of the jaws from such notch to the jaw extremities being inclined to the longitudinal dimension of the jaws.

8. Hæmostatic forceps having jaws constructed to grip at their extremities, but being recessed back from said extremities so as to limit the gripping area, and the jaws being formed with open notches to receive the loop of a cord, and said notches being both at one side of the gripping part and extending back as far as the rear limit of the gripping area, the external surfaces of the jaws from such notch to the jaw extremities being inclined to the longitudinal dimension of the jaws, the outer faces of the jaws being steeply inclined toward their gripping faces.

9. Hæmostatic forceps comprising jaws and connected handle members, said jaws having gripping faces and means for holding the loop of a ligature cord in position embracing said jaws, and a cord-holding clip attached to one of said handle members.

10. Hæmostatic forceps comprising gripping jaws and connected handle members, said jaws having cord-guiding fingers, and a spring clip mounted on one of said handle members and adapted to grip between itself and the adjacent handle member the ends of a cord of which a loop or bight has been engaged with said fingers.

11. Hæmostatic forceps comprising pivoted gripping jaws and connected handle members, said jaws having cord-holding fingers adjacent to their extremities, both of said fingers being at the same side of the forceps, and a cord-holding clip mounted on the side of one of said handle members.

In testimony whereof I have affixed my signature.

JOHN F. CALLAHAN.
